CLAIM

The ornamental design for a combined rack, vegetable peeler, and knife, as shown and described.

DESCRIPTION

FIG. 1 is a front elevational view of a combined rack, vegetable peeler, and knife showing our new design, the rear view thereof being flat and unornamented;

FIG. 2 is a left side elevational view thereof;

FIG. 3 is a right side elevational view thereof;

FIG. 4 is a bottom plan view thereof; and

FIG. 5 is a top plan view thereof.
